DOUBLE CYLINDER CIRCULAR KNITTING
MACHINE

Carlo Camnasio, Giovanni Aurelio Venturelli,
and Giuseppe Colalupo, Milan, Italy, assignors
to Officine Moncenisio, via An. Bauchiero,
Turin, Italy, a corporation of Italy

Application November 10, 1949, Serial No. 126,561
In Italy November 17, 1948

4 Claims. (Cl. 66—14)

1

This invention relates to double cylinder circular knitting machines for stockings and the like, and has for its object a device which will enable the upper cylinder to be fitted exactly.

It is well-known that in the machines of this type great difficulties are met with in fitting the upper cylinder which must be nicely placed in order that the needles in the lower cylinder run exactly into their places in the grooves in the upper cylinder.

Such an operation which must be frequently repeated, for example when the machine is cleaned or overhauled, is a very delicate one and takes up a lot of time and demands great attention on the part of the mechanic.

The device according to the invention mechanises the fitting of the cylinder, reducing the whole operation to the placing of the cylinder in its exact angular position and to the subsequent working of a driving gear.

For this purpose, the clamp by which the upper cylinder is held to the supporting cage is provided on its periphery with pins for fixing the angular position of the assembly and the cage carries, as a support for the said clamp, a rotatable ring comprising sectors of different heights in such a way that by the rotation of the said ring it is possible to ensure that the structure carrying the upper cylinder descends vertically in the direction of its axis, and moves from its highest position to its lowest position which is its normal one.

The accompanying drawings show by way of example a specific embodiment of the invention in which:

Figure 1 is a diagrammatic view partly in section of the upper part of a double cylinder circular knitting machine for stockings to which a device according to the invention has been applied;

Figure 2 is a larger scale section of the upper part of the cage carrying the cylinder together with the members resting on it;

Figure 3 is a corresponding plan view;

Figure 4 shows the development of the driving member, and

Figures 5 and 6 are sections of parts of two superposed cylinders showing the two positions occupied by the upper cylinder during fitting operations.

Fig. 7 is a perspective view of a portion of the crown supporting the upper cylinder, with the parts shown in their initial position at the start of the fitting operation;

2

Fig. 8 is a view similar to Fig. 7, with the parts in their final position.

In Figure 1, the box 1 constitutes the upper portion of the base of a knitting machine in which a gearing 2 is mounted for transmitting the motion of a motor (not shown) to gear wheel 3 which is supported on the collar 4 and integral with the lower cylinder 5. The toothed wheel 3 is connected by a pinion 6, the shaft 7 and a pinion 8 to the toothed wheel 9 integral with the upper cylinder 10 and supported by a clamp 11 on the upper edge or crown 12 of the cage 13 fixed to the upper wall of the box 1. The clamp 11 carries on its periphery two studs 14 (Figures 2 and 3) in the shape of keys which can fit on the circular rim or flange of the crown 12 of the cage 13, these studs being destined to correspond to grooves 15 in the said rim or flange. On the upper side of the rim of the crown 12 rests the lower flat side of a ring 16 (Figure 4), the upper side of which is made up of sections of different heights 17 and 18 (Figure 4) connected together by the gradients 19 in the proximity of the grooves for the keys 14. The ring 16 is provided with a handle 20 by which it may be operated. The assembly comprising the upper cylinder 10 and the toothed wheel 9 rests on the crown 12 of the supporting cage 13 with the ring 16 interposed.

When the upper cylinder 10 is being fitted, the clamp 11 on which the toothed wheel 9 rests, is placed on the top of cage 13 while care is to be taken that the angular position of the clamp 11 is such, that the keys 14 penetrate the grooves 15 arranged vertically in the crown 12.

As a consequence of this fitting operation, the keys 14 happen to ride the ring 16, and the lower face of each key 14 comes to rest on the upper surface of the ring 16.

Consequently while the cylinder 10 is being fitted, the clamp 11, which must support it with its toothed wheel 9, rests with the keys 14 on the highest part 17 of the ring 16 as can be seen in Figure 2, in which the cylinder 10 is spaced away from the lower cylinder 5.

Hereafter, by acting upon the handle 20, an angular displacement of the ring 16 is effected in order to bring underneath the supporting surface of each key 14 a gradient 19 of the contour of the ring 16 and, successively, the section 18 of the said contour.

During this displacement of the ring 16, the lower supporting surface of the keys 14 descends down the gradient 19 and reaches the section 18 of the upper contour of the ring 16. The clamp 11 and, together with it, the crown 12, as well as

the upper cylinder 10, descend gently and uniformly in vertical direction, being guided by the engagement of the keys 14 into the vertical grooves 15 of the crown 12. The lowest position, which the parts occupy at the end of this operation, and which is visible in Fig. 8, is the normal working position of the machine as shown in Fig. 8. In this position the clamp 11 is resting, with the aid of its keys 14, on the sections 18 of the upper contour of the ring 16, which, in turn, rests on the crown 12 of the cage 13.

The two positions, that is to say the highest one before the rotation of the ring 16, and the lowest one or the normal position, are indicated in Figures 5 and 6, where it can be seen that the needles 21 situated in the grooves of the lower cylinder 5 have at the completion of the fitting entered the grooves 23 of the upper cylinder 10.

As can be seen from the preceding, the fitting operation of the upper cylinder is very simple and easy, it being sufficient for the operator to place the supporting clamp 11 of the cylinder exactly in the angular position required which may easily be done due to the keys and the corresponding grooves on the stationary cage, and thereafter rotating the ring 16 so that the upper cylinder 10 descends to the final position, while maintaining itself centred on its axis.

What we claim is:

1. In a double cylinder knitting machine comprising a stationary cage, a clamp on said cage supporting the upper cylinder, a device for fitting said cylinder comprising means to fix the angular position of said cylinder with respect to said stationary cage, a ring rotatably mounted between said cage and said supporting clamp, sectors of said ring comprising adjacent sections of different height, said supporting clamp resting on said ring in the region of said sectors and means for rotating said ring.

2. In a double cylinder knitting machine comprising a stationary cage, a clamp on said cage supporting the upper cylinder, a device for fitting said cylinder comprising keys on said supporting clamp and corresponding guides on the supporting cage to fix the angular position of said

cylinder with respect to the stationary cage, a ring rotatably mounted between said cage and said supporting clamp, sectors of said ring comprising adjacent sections of different height, said supporting clamp resting on said ring in the region of said sectors and means for rotating said ring.

3. In a double cylinder knitting machine comprising a stationary cage, a clamp on said cage supporting the upper cylinder, a device for fitting said cylinder comprising means to fix the angular position of said cylinder with respect to the stationary cage, a rotatable ring mounted between said cage and said supporting clamp and having a flat lower side and an upper side comprising sections of greater height and sections of less height and a gradient between said sections, said supporting clamp resting on said ring in the region of said sections, and means for rotating said ring.

4. In a double cylinder knitting machine comprising a stationary cage, a clamp on said cage supporting the upper cylinder, a device for fitting said cylinder comprising keys on said supporting clamp and corresponding guides on the supporting cage to fix the angular position of said cylinder with respect to the stationary cage, a rotatable ring mounted between said cage and said supporting clamp and having a flat lower side and an upper side comprising sections of greater height and sections of less height and a gradient between said sections, said keys for angular engagement resting on said ring in the region of said sections, and means for rotating said ring.

CARLO CAMNASIO.
